UNITED STATES PATENT OFFICE.

ARCHIE THOMSON, OF CHATTANOOGA, TENNESSEE.

BALANCED SLIDE-VALVE.

SPECIFICATION forming part of Letters Patent No. 337,714, dated March 9, 1886.

Application filed December 7, 1885. Serial No. 184,979. (No model.)

To all whom it may concern:

Be it known that I, ARCHIE THOMSON, a resident of Chattanooga, in the county of Hamilton and State of Tennessee, have invented 5 certain new and useful Improvements in Balanced Slide-Valves, of which the following is a specification.

My invention relates, first, to means employed for utilizing steam to counterbalance 10 in part or wholly the pressure upon the valve; second, it relates to means for oiling automatically the valves' and operative parts, all of which will be fully set forth in the description of the accompanying drawings, making a part 15 of this specification, in which—

Figure 1 is a central vertical cross-section of my improvement. Fig. 2 is a transverse vertical section. Fig. 3 is a top plan view of the oil or check valve. Fig. 4 is a section on 20 line $\alpha\alpha$, Fig. 2.

A represents the steam-chest, which is of ordinary construction.

12 represent the induction and eduction passages leading into the cylinder.

25 B represents a slide-valve, which is constructed to operate according to the common ordinary slide-valve by covering and uncovering the ports $a a$, opening into the induction-passages.

30 b represents the exhaust-chamber between the ports $a a$, which is also of ordinary construction, and is provided with the ordinary escape-pipe.

C represents the valve-stem; c, the stuffing-box, which valve and stem are operated by the ordinary link and eccentric movement.

35 D represents an upward supplemental extension of the steam-chest.

E represents a supplemental cylinder, which 40 is preferably connected to the extension D by screw-bolts. Extension D opens freely into the steam-chest.

F represents a guide, which is provided with two openings, d, for the free admission of 45 steam into the supplemental cylinder E.

G represents a supplemental piston, reciprocating within the cylinder E. It is connected to the valve by a piston-rod, 3, and a link, 4. The top of the valve is recessed to 50 receive the end of the link 4, and a transverse

pin, 6, passes through a slot in the link to hold it in position.

5 represents a pin for connecting the link 4 to the piston-rod 3, which rod passes through an opening in the head of the extension D, 55 which is shown in plan, Fig. 4.

12 represents a seat on which the piston G rests when there is no pressure in the steam-chest.

Piston G may be packed in the ordinary 60 manner, if desired, by packing-rings or other equivalent means.

As valve B is moved forward link 4 and rod 3 reciprocate the piston G simultaneously with the movement of the valve B. In order to 65 avoid the adjustment of the parts I elongate the openings in the link 4 at the upper end, below the pin 5, and at the lower end above the pin 6.

The dotted lines in Fig. 1 show the extent 70 of the movement of the valve at a full stroke of the valve to the left or forward. The full lines show the valve in the act of passing the center, and moving forward to cover the port leading to passage 2, and to uncover the port 75 leading to passage 1, for exhausting through passage 1.

The piston G with each full movement of 80 the valve is drawn down and stops at the position shown by dotted lines, Fig. 1.

The area of the valve B is shown larger than the area of the piston G, and hence the pressure upon the valve is slightly greater than the pressure upon the piston, the piston only 85 in part counterbalancing the weight of steam upon the valve; but the areas may be changed, so as to have an exactly-balanced valve, if desired.

In order to prevent the movement of the piston G and the clattering of the valve when 90 the valve is in motion—as in a locomotive—when not using steam, I provide slots for the pins 5 and 6 in the connecting-rod 4, so that a full movement of the valve will operate the link without operating the piston. The elongation of the slots for the pivot-holes for the pins 5 and 6 is together equal to the entire distance which the piston G moves. When the steam is off, the piston G drops down to its position, and the elongations in the link 4 95 100

allow it to remain stationary, the link 4 moving with the valve, the slots taking up the motion of the link 4; but once steam is admitted into the steam-chest the pressure of the steam 5 operates upon the piston G, takes up the lost motion in the slots of link 4, and brings the parts to the position as shown in Fig. 1.

It is necessary to employ suitable means for lubricating piston G, and it is desirable at the 10 same time to lubricate the seat for the valve B, as well as the main cylinder and piston. To accomplish this I have provided the following instrumentalities:

H represents the oil-cup the stem of which 15 screws into the cap I of the cylinder E, and the piston-rod 3 extends through the piston G a sufficient distance to come vertically under the orifice in the stem of the oil-cup. The piston-rod 3 is provided with a hollow opening 20 or oil-passage, e, leading through it. The lower end of this rod 3 is enlarged, and receives the check-valve 7.

8 represents a pin, which stops the descent 25 of the valve 7.

9 represents a continuation of the opening in the rod 3, through which the oil passes freely when the valve has dropped down onto its seat 8.

The valve 7 is an ordinary three-winged 30 valve, the oil passing between the wings of the valve, out the opening 9, and down into the opening 10 in the cap of the valve B, where it is received and held when the engine is idle, and flows over the edges and down through 35 onto the seat of the valve, through the ports into the passages 1 and 2, for oiling the cylinders and piston.

When steam is admitted into the chest and the piston G rises, the passage 9 is sufficiently 40 large to allow the steam to freely enter and raise the valve 7 against its seat, which stops the admission of oil into the steam-chest, valves, and cylinders of the engine when it is in operation. As soon as the steam is cut off the

oil-valve drops back to its seat, and the oil is 45 received into the reservoir 10, for oiling the engine when it is in motion. The check-valve 7 prevents the escape of steam into the oil-cup when the steam is applied.

I do not wish to limit myself to the form of 50 check-valve 7, as any form of valve may be employed to close the oil-passage which will admit oil into the steam-chest when the valve is open.

What I claim as my invention is— 55

1. In combination with a slide-valve and a supplemental piston, a link provided at each end with a slot, and pins passed through said slots for connecting the link to the valve and piston, whereby the piston is allowed to remain idle when the valve is moving without steam-pressure, substantially as described. 60

2. In combination with a slide-valve and a supplemental piston, a piston-rod having a valved oil-passage leading into the valve-chamber, and a link for connecting said valve and piston-rod, substantially as described. 65

3. In combination with a slide-valve, a valve-chamber, a supplemental piston, and a piston-chamber communicating with the valve-chamber, a piston-rod having a valved oil-passage, a link having a slot at each end, and pins for connecting said link to the piston-rod and slide-valve, substantially as described. 70

4. In combination with the supplemental 75 piston G and piston-rod 3, having the oil-passage leading through said rod, the valve 7, operated by the pressure of the steam to close the oil-passage when the steam-pressure is operating in the chest, substantially as herein specified. 80

In testimony whereof I have hereunto set my hand.

ARCHIE THOMSON.
